UNITED STATES PATENT OFFICE

LEONARD DODSON AND JAMES DODSON, OF CHICAGO, ILLINOIS

STRINGED MUSICAL INSTRUMENT

Application filed October 24, 1927. Serial No. 228,415.

This invention relates to certain novel improvements in stringed musical instruments and comprises the novel combination and arrangement of parts hereinafter described and claimed.

- It is among the objects of our invention to provide a musical instrument of the foregoing named character which will embody an arrangement whereby certain of the strings thereof may be operated on by a suitable instrument so as to produce melody while others of the strings thereof may be operated thereon so as to produce accompanying chords to said melody.
- Another object of the invention is to provide an arrangement whereby the melody strings may be arranged in groups and such that said strings will be disposed in substantially parallel relation.
- A further object of the invention is to arrange the melody strings such that one of the ends thereof will be connected to suitable tuning posts and such that the other end thereof will be connected to mountings arranged such that the playing implement may be readily shifted from one of said strings to the other and such that said implement will act on only one of said strings when in certain positions.
- A still further object of the invention is to provide a musical instrument of the foregoing character which will be simple and economical in construction and simple in operation.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a plan elevational view of a preferred embodiment of our invention.

Fig. 2 is a perspective detail view of the securing element for the end of the melody strings opposite the end secured to the tuning posts.

Fig. 3 is a detail view taken substantially on the line 3—3 of Fig. 1.

Figs. 4, 5, 6, 7, and 8 are fragmental side views depicting various modifications of mounting the melody strings on the anchoring element depicted in Fig. 2.

Fig. 9 is a sectional detail view taken on 55 the line 9—9 on Fig. 8.

Fig. 10 is a partially diagrammatic side elevational view of the device as illustrated in Fig. 1.

Referring to the drawings wherein the 60 preferred embodiment of our invention is illustrated, it may be seen that we provide a sound box 10 substantially similar to the sound box of a typical so called string instrument. In the present instance we show 65 the sound box 10 as being substantially rectangular but it is to be understood that it might be formed of any desired and suitable configuration. An opening 11^a is provided in the top wall of the sound box for purposes 70 well understood in the art.

On the upper side of the sound box 10 at each end thereof blocks 11 and 12 are mounted and strips 13 and 14 are secured to said upper side and are disposed so as to extend 75 between said blocks 11 and 12 contiguous the edges of the sound box 10.

Juxtaposed the inner transverse edge of the block 11, a fret 15 is secured and mounted on the upper side of the block 11 behind fret 80 15 and disposed in staggered relation, are a plurality of tuning posts of the usual form which are indicated in drawings by 16. It is desirable that the blocks 11 and 12 and the strips 13 and 14 be of equal height. As is 85 clearly shown in Fig. 1, at spaced apart intervals along the strips 13 and 14 anchoring elements 17 are mounted in aligned relation. As is clearly shown in Fig. 2 the anchoring elements 17 include screw threaded lower 90 end portions 18 and in the upper surfaces thereof a groove 19 is provided. An opening 21 is provided in the anchoring element 17 and extends therethrough in parallel relation to the groove 19.

One of the ends of each of the melody strings 20 is individually connected to the anchoring elements 17 in a manner to be described and then the strings are brought up along the anchoring elements and are dis- 95 100

posed in the grooves 19 in the heads thereof in a manner such that less than one-half of the diameter of the string will be disposed in the groove so that the major portion thereof will be disposed above the upper extent of the element 17. From the grooves 19 the melody strings 20 extend through slots in the fret 15 and then each of the ends are respectively connected to one of the tuning posts 16. The melody strings 20 are disposed so as to extend between the tuning posts 16 and the anchoring elements 17 in a manner such that the strings representing the notes of a diatonic scale will be suitably arranged and such arrangement will be readily apparent to any one skilled in the art.

As is best illustrated in Fig. 10 the anchoring elements 17 which are located nearest to the fret 15 are of greater height than the anchoring elements 17 which are located most remote from said fret and the anchoring elements interposed between the above named elements are each successively shorter than the element juxtaposed thereto on the side thereof towards said fret. Therefore, it is apparent that when an operating implement such as a violin bow is drawn across one of the melody strings, preferably adjacent the anchoring element for said string, said bow will not contact with the other of the strings since they will lie in a lower horizontal plane. As is apparent by referring to Fig. 1, the anchoring elements on the strips 13 and 14 are equally spaced apart on said strips and are also disposed in longitudinal alignment thereon. It will also be noted that the anchoring elements are in alignment transversely of the sound box 10. One arrangement of the melody strings 20 is that the string for the first note of the diatonic scale will be led to the first anchoring element on the strip 13 while the string for the second note will be led to the first anchoring element on the strip 14 and the string for the third note will be led to the second anchoring element on the strip 13 and this manner of connecting is carried out until each of the tuning posts 16 and anchoring elements 17 have interconnected.

The ends of the melody strings 20 adapted to be connected to the anchoring elements 17 may be fixed thereto in a number of different ways. The anchoring elements 17 are adapted to be screw threaded into suitable openings in the strips 13 and 14. In Fig. 3 we show the portion 18 of the anchoring elements 17 as also entering the upper side of the sound box 10.

In Fig. 3 we show the melody string 20 as being directed through the groove 19 and then downwardly along the anchoring element 17 and through the opening 21. A loop 22 is provided on this end of the melody string 20 which is adapted to be anchored in position by being inserted over a pin 23 that is angularly driven into the strip 14.

In Fig. 4 we show the end of the melody string 20 which is directed through the groove 19 in the outermost of the anchoring elements 17 as being led through the opening 21 of said element and then this end is looped around the next succeeding anchoring element as indicated at 24. This construction would be successively carried out with the exception of the foremost of the anchoring elements wherein in the end of the melody string may be secured in any approved manner such as that shown in Fig. 3.

In Fig. 5 we show the end of the melody string 20 as being directed through the groove 19 and then being led downwardly and having a loop 26 formed therein which is inserted over the pin 27 which is angularly driven into the strip 14. This construction would obviate the necessity of the opening 21.

In Fig. 6 we show the end of the melody string 20 as being directed through the groove 19 and then downwardly along the anchoring element 17 and then through the opening 21. A suitable knot such as 28 is then formed at this end of the string so as to prevent said end passing back through the opening 21.

In Fig. 7 the end of the melody string 20 is directed through the groove 19 and is then twisted around the anchoring element 17 and then is led through the opening 21 so as to provide a snubbing action and the end of the string bent downwardly as at 29 so as to prevent passage back through the opening 21. In Figs. 8 and 9 we depict a construction wherein the string 20 is led through the groove 19 and then downwardly over the edge of strip 14 and a loop 30 is provided at the end of the string which is inserted over a pin 31 which is driven into the side of the strip 14 in an angular manner as indicated at Fig. 9. A spacing strip 32 is interposed between the side of the strip 14 and the string 20 so as to prevent the contact of said string with the strip 14. If desired a suitable molding such as 33 may be secured to the side of the strip 14 so as to conceal the pins 31 and thus provide a more pleasing appearance for the instrument.

If so desired, relatively thin strips 34 and 35 may be disposed over the strips 13 and 14 in the region of the anchoring element 17 as is clearly illustrated in Fig. 1. Suitable markings will be provided on these strips which will facilitate the playing of the instrument by a person not particularly skilled in music.

As has been pointed out anchoring elements are arranged such that when a violin bow or the like is drawn across one of the strings adjacent to the anchoring element thereof said bow will not contact with the other string. Further, due to the fact that each of the anchoring elements is of a successively greater height than the one juxtaposed thereto and since the melody strings are led around the anchoring element in the

direction toward the next lowermost post, it is apparent that the bow will be expeditiously guided onto the succeeding string or onto any string desired. This formation of the 5 anchoring elements facilitates the guiding of the bow and additional guiding members are not required.

A fret 36 is secured to the upper side of the sound box 10 between the strips 13 and 10 14 in spaced relation to the block 11. A fret 14 is secured on the upper side of the block 12 contiguous the inner edge thereof. A plurality of pins 38 are fixed in the upper side of the block 10 and are disposed in staggered 15 relation. The pins 38 are preferably disposed between the fret 36 and the block 11. A plurality of tuning posts 39 are mounted on the upper side of the block 12 and these tuning posts are disposed in staggered relation. A 20 plurality of strings 40 are stretched between the frets 36 and 37 and are connected to the pins 38 and the tuning posts 39. The strings 40 are arranged in juxtaposition to the upper side of the sound box 10 and are arranged 25 in a plane below the plane of strings 20. As is best illustrated in Fig. 1, the strings 40 are preferably arranged in grooves. By manipulating through the medium of a pick in a manner well understood in the art the 30 strings of the groups chords may be produced for accompaniment with the melody played on the strings 20.

It is apparent that if desired the blocks 11 and 12 and the strips 13 and 14 may be 35 omitted and the appurtenances shown and described as being mounted thereon may be directly mounted on the upper side of the sound box 10. While we have illustrated and described the melody strings as being connected 40 in one manner it is apparent that other analogous arrangements might be used without departing from the purview of our invention. We particularly wish to accent the fact that the novel formation of the anchoring 45 elements 17 and the method of securing the melody strings thereto provides sufficient guiding means for the bow or other playing instrument and thus the necessity of extraneous guiding elements is obviated.

50 While we have illustrated and described the preferred form of construction for carrying our invention into effect, this is capable of variation and modification, without departing from the spirit of the invention. We, 55 therefore, do not wish to be limited to the precise details of construction set forth, but desire to avail ourselves of such variation and modifications as come within the scope of the appended claims.

55 Having thus described our invention, what we claim as new and desire to protect by Letters Patent is:

1. A securing element for musical strings including a body portion having an opening 60 extending therethrough, and said body por-

tion having a shallow groove formed in the upper end thereof adapted to extend parallel to said opening.

2. A securing element for musical strings including a body portion having an opening 65 extending therethrough, said body portion having a shallow groove formed in the upper end thereof adapted to extend parallel to said opening, the lower end of said body being screw threaded whereby said element may 70 be mounted on a musical instrument.

3. In combination with a stringed musical instrument, an anchoring element having an opening extending therethrough in the body portion thereof and a shallow groove in the 75 upper end thereof disposed parallel to said opening, the string being disposed in said groove and then downwardly along said body portion and then through said opening, and means on the end of said string adapted to 80 prevent said string passing back through said opening.

4. A securing element for musical strings including a body portion having an opening 85 extending therethrough, said body portion having a groove formed in the upper end thereof adapted to be of less width and depth than the diameter of the string to be disposed therein, said groove being arranged so as to extend through said body portion in parallel 90 relation with said opening.
